CLAIM

The ornamental design for a voice message holiday ornament, as shown.

DESCRIPTION

FIG. 1 is an exploded front perspective view of a voice message holiday ornament showing my new design without a picture being displayed thereby;
FIG. 2 is an assembled front perspective view thereof;
FIG. 3 is an assembled front elevational view thereof with a picture being displayed thereby;
FIG. 4 is an assembled front elevational view thereof without a picture being displayed thereby;
FIG. 5 is an assembled top elevational view thereof;
FIG. 6 is an assembled bottom elevational view thereof;
FIG. 7 is an assembled back elevational view thereof;
FIG. 8 is an assembled left side elevational view thereof; and,
FIG. 9 is an assembled right side elevational view thereof which is a mirror image of the assembled left side elevational view.
